UNITED STATES PATENT OFFICE

LOUIS JENSEN AND FREDERICK C. REUCKER, OF CHICAGO, ILLINOIS, ASSIGNEES TO
UNITED AUTOGRAPHIC REGISTER CO., OF CHICAGO, ILLINOIS, A CORPORATION OF
ILLINOIS

VARIABLE SPEED MECHANISM

Application filed September 9, 1929. Serial No. 391,484.

This invention relates particularly to a variable speed mechanism.

The primary object is to provide an improved mechanism of the character indicated. A further object is to provide an improved variable-speed pulley device which can be easily set or adjusted to give the desired speed of transmission.

The invention comprises, further, the embodiment of variable-speed mechanism in apparatus for supplying continuous-form stationery and folding the same transversely in zig-zag fashion.

The invention is illustrated in a preferred embodiment in the accompanying drawings, in which—

Fig. 1 is a broken elevational view showing the invention embodied in apparatus comprising a folding machine and an unwinding machine which is actuated from the folding machine; Fig. 2, a broken perspective view illustrating the manner in which the stationery strips are taken from a supply roll and brought into superposed relation in passing to the folding machine; Fig. 3, a broken elevational view of the variable-speed pulley device removed from the folding machine; Fig. 4, a broken, partly sectional view of the device shown in Fig. 3, the view being taken from the left of Fig. 3; Fig. 5, a vertical sectional view taken as indicated at line 5 of Fig. 4; and Fig. 6, a perspective view of one of the adjustable segments with which the variable speed pulley is provided.

In the illustration given, A designates a folding machine for transversely folding multiple-strip stationery; B, a variable-speed pulley mounted on the frame of machine A and actuated by the driving mechanism thereof; C, an unwinding machine serving as a source of supply for machine A, the machine C being equipped with a driving pulley C'; and D, a transmission device or belt connecting the variable-speed pulley B with the driving pulley C'.

It may be stated preliminarily that, according to one method employed in producing continuous-form stationery, a web of paper is passed through a printing press to print forms in parallel rolls on the web; the web is

slitted to separate the continuous forms; and the strips are wound upon a storage roll. Such a roll of strips may be placed on the unwinding machine C and fed to the folding machine A, the multiple strips being allowed to drape or form a loop between the two machines.

The folding machine A may be of any suitable construction. The machine partially illustrated in Fig. 1, is fully described in the Jensen and Winters application No. 377,803, filed July 12, 1929. Only such description of the folding machine as may be necessary to the understanding of the present invention will be given in the present application.

The machine A comprises a frame 1 provided with a strip-guide 2 for the paper strips 3. The frame is further equipped with a strip-guide 4 equipped with individual guides for the several strips of paper. The strips pass from the guide 4 to a reciprocating distributor 5, which co-acts with reciprocating folder-plates 6 and 7, which effect the transverse folding of the strips in zig-zag fashion.

The folded strips drop upon a transversely extending conveyor 8 which is inclined somewhat, the high end of the conveyor being shown in Fig. 1, and the delivery end being at the other side of the machine.

The distributor and associated folding mechanism are actuated through the medium of a driving mechanism 9, which, in turn, is actuated by an electric motor. (Not shown.)

The driving mechanism 9 is shown equipped with a gear wheel 9^a which operates 80 the variable-speed pulley B.

The device B comprises a bracket, or mounting, 10 which has a base portion 10^a provided with perforations 10^b adapted to receive bolts (not shown) by means of which the bracket is mounted on the frame 1; a stub-shaft 11 fixedly mounted in the upper portion of the bracket 10 and projecting laterally therefrom; a pulley 12 having a bore fitted with a bearing 13 journaled on the shaft 11; peripheral segments 14 disposed between flanges 15 with which the body of the pulley is provided, the segments 14 being equipped with inwardly extending stems 14^a provided at their inner ends with beveled heads 14^b; 100

a series of wedge-blocks 16 mounted in slots or openings with which the pulley 12 is provided, said blocks having beveled surfaces 16^a co-acting with the beveled surfaces of the heads 14^b; a collar 17 rigidly secured to the pulley 12 as by means of screws 17^a, said collar being provided with spring-sockets 17^b fitted with plugs 17^c; coil springs 18 housed in said sockets and opposed to the wedge-blocks 16; a gear 19 rigidly secured to the pulley 15, as by means of cap screws 19^a; a wedge-adjusting pinion 20 having a tapped bore engaging a threaded portion 20^a of the stub-shaft 11; and an adjusting shaft 21 journaled in the bracket 10, said shaft being equipped at one end with a pinion 21^a meshing with the pinion 20, and equipped at the other end with a fixedly secured crank-wheel 21^b.

The gear 19 actuates the pulley 12, and is itself actuated by the gear 9^a of the folding machine.

The bearing 13 with which the pulley is provided is confined between collars 22 and 23 which are adjustably fitted on the shaft 11. Between the outer end of the bearing 13 and the collar 22 is interposed an anti-friction thrust bearing 24.

As shown in Fig. 6, each rim-segment 14 has its stem portion slidable through a collar 25 which is provided with a recess 25^a. A spring 26 is interposed between the collar mentioned and the head 14^b. The shank 14^a is formed separately from the segment and has a reduced threaded extremity which engages a tapped opening with which the central portion of the segment is provided.

The segments may be applied to the pulley from the outside, the stem being entered through the radial opening or socket 27 in the pulley, after which the collar 25 may be secured in position by a set screw 28 whose inner end engages the recess 25^a. Thus, the segment will be held inward yieldingly. Expansion may be effected by turning the pinion-equipped nut 20 in proper direction to force the wedge-blocks 16 inwardly.

An anti-friction bearing 29 is interposed between the nut 20 and the wedge-blocks.

The gear 19 is annular, and the inner portion of the pinion 20 and the bearing 29 are of small enough diameter to permit the nut to follow the wedge-blocks. The annular gear 19 is shown fitted over a shoulder 30 with which the pulley 12 is provided.

In practice, the crank-equipped shaft 21 may extend across the machine A; or it may, in any event, be of sufficient length to enable the crank wheel 21^b to be operated from the side of the machine opposite that shown in Fig. 1.

The radius on which the segments 14 are struck may correspond with a circle about midway between the inner and outer limits of expansion of the pulley.

The roll unwinding machine C comprises

a frame 31; a roll-shaft 32 journaled in the lower portion of the frame; a driven feed roll 33 and a co-acting idler roll 34; a driven feed roll 35 journaled in the upper portion of the frame, a driven feed roll 36 disposed at right angles to the feed roll 35 and having co-acting therewith a spring-held idler roll 37; and obliquely extending turn-bars 38 carried by bracket-members 38^a mounted on the upper cross bar 39 of the frame.

Strips 3 are drawn from rolls 3^a mounted on the shaft 32. The strips pass over the feed roll 33, under the companion idler roll 34, but over the feed roll 35 and under the turn-bars 38, then at right angles over the turn-bars, and thence between the rolls 36 and 37. Between the machines A and C the strips form a loop 3^b.

The pulley C' is mounted on a shaft 40 connected by beveled gears 41 to the shaft of the feed roll 33. The shaft just mentioned is connected by a belt 42 to the shaft of the feed roll 35. The last-mentioned shaft is connected by beveled gears 43 to the shaft of the feed roll 36.

The turn-bars 38 are set obliquely at a 45° angle to enable the paper strips to be turned to an angle of 90° after passing over the feed roll 35. Each turn-bar is shown as comprising a flat strip 38^b carried by the bracket member 38^a, and a slotted tubular member 38^c fitted on one edge of the strip so as to give a rounded surface over which the paper strip is turned.

In the operation of the apparatus illustrated, the paper strips are drawn into the distributing and folding mechanism of the folding machine by the action of said mechanism, the strips being drawn from the loop 3^b as required. The segments of the variable-speed pulley B are intended to be adjusted in such manner as to drive the roll unwinding machine at proper speed to maintain the loop 3^b. In practice, the loop 3^b may lengthen or shorten somewhat due to various causes. Should the operator discover that the loop is lengthening unduly, correction may be made by adjusting the rim-segments 14 inwardly somewhat, thus slowing down the driven speed of the roll unwinding machine. On the other hand, if the loop 3^b tends to shorten, this may be overcome by expanding the variable-speed pulley somewhat, which has the effect of speeding up the operation of the roll-unwinding machine.

The foregoing detailed description has been given for clearness of understanding only, and no unnecessary limitations should be understood therefrom, but the appended claims should be construed as broadly as permissible, in view of the prior art.

What we regard as new, and desire to secure by Letters Patent, is:

1. In apparatus of the character set forth: a roll-unwinding machine equipped with

turn-bars and with strip-feeding mechanism, including feed rolls which engage the strips after they pass about the turn-bars; a strip-folding machine equipped with driving mechanism; and variable-speed transmission mechanism between said driving mechanism and said strip-feeding mechanism.

2. In means of the character set forth: a roll unwinding machine equipped with strip-feeding mechanism; a strip-folding machine for which said roll-unwinding machine serves as a source of supply, said strip folding machine being equipped with driving mechanism, and a variable-speed pulley mounted on said strip-folding machine actuated by the driving mechanism thereof, said variable-speed pulley being connected by a flexible transmission member with said strip-feeding mechanism.
